FOREARM FRACTURE TRACTION
APPLICATOR

Robert K. Hart, Croswell, Mich.

Application October 27, 1949, Serial No. 123,957

3 Claims. (Cl. 128—84)

1

This invention relates to surgical implements particularly of the type adapted for setting bones in forearms, and in particular rubber tubes providing suction cups for positioning over a thumb and fingers of a hand to provide gripping means for applying traction to the forearm, and a bracket or stand having a shoe for positioning against the forearm with a cross bar for holding the ends of the rubber tubes opposite to the ends rolled over the fingers and thumbs of the hand.

The purpose of this invention is to provide means for creating traction in forearms wherein muscle resistance is overcome and fractures are reduced and also in which the correct position of the forearm is maintained to facilitate the application of splints or casts thereto.

The usual finger traps cause trauma to the tissues and it is, therefore, desirable to provide means for gripping the fingers wherein less trauma to the tissues is provided and skeletal traction is dispensed with. With this thought in mind this invention contemplates rubber tubes with weights in the ends thereof wherein with the ends of the tubes opposite to the ends in which the weights are positioned placed over the thumb and fingers of a hand the tubes may be readily and quickly tied to a stationary device which, with an arm positioned against the forearm provides traction on the forearm to facilitate treating fractures and the like.

The object of this invention is, therefore, to provide an improved method of gripping the fingers of a hand which causes less trauma to the tissues and dispenses with skeletal traction.

Another object of the invention is to provide a device for placing traction in a forearm which enables a doctor to set the arm while under traction and without the aid of an office assistant or the like.

A further object of the invention is to provide an instrument for applying traction to a forearm fracture which is of a simple and economical construction.

With these and other objects and advantages in view the invention embodies a plurality of thin rubber tubes with weights in one of the ends thereof and a stand having a cross bar thereon and also having an extended arm with a shoe at the end, the said shoe being positioned to contact the upper arm of a patient with the tubes positioned on the fingers of the hand of the arm of the patient.

Other features and advantages of the invention will appear from the following description

2

taken in connection with the drawings wherein: Figure 1 is a side elevational view illustrating the application of the instrument to the forearm of a patient.

Figure 2 is a plan view of the instrument illustrated in Figure 1.

Figure 3 is a detail illustrating one of the thin rubber tubes with part of the tube broken away showing a weight mounted therein.

Referring now to the drawings wherein like reference characters denote corresponding parts the forearm traction instrument of this invention includes a plurality of rubber tubes 10 having weights 11 therein and a stand 12 having a cross bar 13 thereon and also having an extended arm 14 with a shoe 15 on the outer end.

The tubes 10 are provided with rolled ends as indicated by the numeral 16, and the weights 11 are fixedly mounted in the opposite ends by spring rings 17 which hold the wall of the tubing in annular grooves 18 in the outer surfaces of the weights. It will be understood that the weights may be secured in the tubes by any other means.

With the weights provided in the ends of the tubes opposite to the ends placed over the fingers, as illustrated in Figures 1 and 2 the ends of the tubes with the weights therein may readily be wrapped over or secured to the cross bar 13 and also readily removed therefrom. With the weights placed in the ends of the tubes, the tubes may be placed over the cross bar 13 with the ends in which the weights are positioned hanging downwardly whereby the weights provide means for holding the extended ends of the tubes over the cross bar. The weights may also be used as illustrated in Figure 1 with the ends in which the weights are positioned wrapped over the cross bar and extended over the tubes or the ends with the weights therein may be tied over the bars as shown in Figure 2.

The cross bar 13 is adjustably mounted by a fitting 19 on the bracket 12 and the fitting is provided with a thumb nut 20 on a threaded stud 21 whereby the elevation of the cross bar may be adjusted to accommodate the patient.

The upper end of the stand 12 is bent over providing a horizontally disposed section 22 and an angularly disposed part 23 to which the arm 14 is attached by a fitting 24.

The shoe 15 which is arcuate in cross section is provided with a rolled lower edge 25 to rest upon the inner surface of the elbow of an arm, and a socket 26 through which the shoe is mounted on the outer end of the arm 14.

The lower end of the stand 12 may be provided with a rubber plug or cap 27 to facilitate holding the stand in position and to prevent marring or scratching a surface upon which the stand is positioned.

With the parts arranged in this manner the thin rubber tubes are placed over the fingers and thumb of a hand as illustrated in Figures 1 and 2 and with tension placed on the tubes and extended ends thereof secured to the bar 13 by tying as shown traction is provided in the forearm of an arm against which the shoe 15 of the bracket or stand is positioned.

The rubber tubes or cups may readily be removed from the fingers by rolling the ends thereof and the opposite ends may readily be removed from the cross bar 13.

With the arm supported in this manner traction is created in the forearm and a bone may be set and splints or casts applied with the arm maintained in the natural position.

It will be understood that modifications may be made in the design and arrangement of the parts without departing from the spirit of the invention as defined in the claims.

What is claimed is:

1. A forearm traction applicator comprising a thin rubber tube which causes suction when placed over a finger whereby the tube is secured to the finger, and a weight in the opposite end of the tube for facilitating holding the extended end of the tube to provide tension therein.

2. A forearm traction applicator comprising a plurality of thin rubber tubes which when placed

over the fingers of a hand cause suction securing the tubes to the fingers, a stand having a cross bar thereon to which the outer ends of the tubes are removably attached, and a shoe extended from said stand and positioned to engage the upper arm of a forearm on the fingers of which the tubes are positioned.

3. A forearm traction applicator comprising a plurality of thin rubber tubes which when placed over the fingers of a hand cause suction securing the tubes to the fingers, a stand having a cross bar thereon to which the outer ends of the tubes are removably attached, and a shoe extended from said stand and positioned to engage the upper arm of a forearm on the fingers of which the tubes are positioned, said tubes having weights in the extended ends thereof, for retaining the ends of the tubes over the cross bar.
